UNITED STATES PATENT OFFICE.

JOHN ROGER OLIVER, OF MEDFIELD, MASSACHUSETTS, ASSIGNOR TO REECE SHOE MACHINERY COMPANY, OF BOSTON, MASSACHUSETTS, A CORPORATION OF MAINE.

SEWING MACHINE.

Application filed May 9, 1924. Serial No. 712,035.

This invention is a novel sewing machine, and relates more especially to a shoe stitching machine of the class known as a welt-and-turn stitching machine, in which 5 the shoe insole is attached to the shoe upper, and, in some cases, also to the welt strip. One example of welt-and-turn-stitching machine is shown in prior Patent 1,361,952 granted December 14, 1920 to Zaleski and 10 Schoenky, although the present invention is applicable to shoe stitching or other sewing machines of different types.

The present invention embodies improvements pertaining more especially to certain 15 of the stitching instruments shown in the prior patent, including the work rest or so-called bumper and the welt feeding and applying member or so-called back gage. The actuating means or operating connections 20 for these instruments include, in the prior patent, certain pawls or dogs cooperating with toothed racks, for holding the stitching instruments in proper position during a certain part of the cycle in the formation of 25 each stitch. This form of mechanism has proven disadvantageous. An improved mechanism has been disclosed in prior application of Zaleski Serial Number 580,276 filed August 7, 192.

30 The principal object of the present invention is to afford a sewing machine in which the mechanisms and operations referred to are improved as compared with the prior structures, and are simple, quick- 35 acting, effective and durable. Other objects and advantages of the present invention will be explained hereinafter or will be apparent to those skilled in the art. To the attainment of such objects and advantages the 40 present invention consists in the novel sewing machine and the novel mechanisms, combinations, arrangements and devices herein illustrated or described.

In the accompanying drawings forming a 45 part hereof Fig. 1 is a left elevation of the pertinent parts of a shoe stitching machine embodying the present invention.

50 Fig. 2 is a right elevation showing certain of the same parts and others not seen in Fig. 1.

Fig. 3 is a plan view taken partly in section on the line 3—3 of Fig. 1.

Fig. 4 is a similar plan view taken partly in section on the line 4—4 of Fig. 1.

Fig. 5 is an enlarged right elevation of 55 certain parts seen in Fig. 2.

General features of construction and operation of the sewing machine, not forming a part of the present invention, may be ascertained by reference to the prior patent and 60 application referred to, and others, and therefore are not herein illustrated except so far as convenient for the description of the present invention.

The herein illustrated machine may comprise the usual stitching instruments including the work-rest or bumper A against which the workman holds the shoe X during stitching, also the channel guide B which engages with the channel in the sole x, also the 70 oscillating, curved, hooked needle C, operated to penetrate the welt w, the upper y and the lip of the insole x, also the looper D, operated to place the thread in the barb in the needle, also the thread finger E co-operating with the looper, a feed device or awl, and the back gage H against which the work contacts at certain times and which also serves as a guide and feeder for the strip or welt. The usual take-up will be understood. The work-rest A is mounted at the forward end of a sliding shank a and the back gage H at the forward end of a similar shank h, through which these two instruments are actuated or controlled. 85

The general operation may be as in the prior patent and application. At the starting position of the machine both the work-rest and back gage are free, that is are held forwardly by spring pressure but can yield rearwardly to adapt themselves to the position of the shoe. During the period in which the needle is retracting from the work the work-rest is locked forward, thus holding the work forward and resisting the rearward pull of the needle. At all other times the work-rest is free and resiliently adjusts itself according to the manipulation of the shoe. The shoe of course is fed forwardly while the needle is out of the work and at such times is guided by the channel guide B. The back gage H feeds the welt strip to the stitching point. While the work is stationary, and after being disengaged by the needle, the back gage is retracted, drawing 100 welt from the supply, later moving forwardly and laying the welt in stitching position. The retraction of the back gage is not until 105

after the needle has retracted out of the work, it being locked forward in the meanwhile, thus assisting the work-rest to hold the shoe forward during the retraction of the 5 needle.

The machine may comprise an upright frame wall 10 which supports much of the mechanism and forms a bearing for the stitching shaft 11, which may be a crank 10 shaft having a crank 13 at the right or inner side of the wall, from which the needle and other instruments may take their movement, as in the prior patent and application.

15 In the illustrated embodiment of the present invention the work-rest and back gage are controlled from a single cam disk 15 secured to the shaft at the left of the frame wall. The disk 15 is shown as having two 20 cam grooves, an inner one 16 and an outer one 17.

The yielding forward pressure upon the work-rest A may be effected by a spring 18, seen in Figs. 2 and 4. Likewise the back 25 gage H may be pressed forwardly yieldingly by a spring 19 shown in Figs. 2 and 3. The shanks *a* and *h* of these two members are shown slidingly fitted in grooves formed in the right side of the frame wall, and near 30 their forward ends they are confined therein by an attached confining plate 20.

The retraction of the back gage may be effected by the following mechanism. A follower 22 engages the cam groove 17 and is 35 mounted on an arm 23 of a lever fulcrumed at 24 and having a downward arm 25, the extremity 26 of which constitutes a bunter, arranged to cause the retracting movements of the shank *h* by striking a rearward blow 40 against a lug 27 projecting leftwardly from the shank. Leather washers 28 may be interposed between the bunter 26 and the lug 27, with a pin 29 passing through and holding the parts in position. The timing is 45 such that after the needle has retracted and the shank *h* has been released it is bunted rearwardly to the proper extent so as to effect feed of welt as described and to draw the back gage away from the shoe so as not 50 to disfigure the leather during the feeding movement. The extent of retracting movement may be adjusted through a plate 30 longitudinally adjustable on the shank *h* and carrying the lug 27.

55 Although the back gage normally comes forward, when released, into contact with the shoe, it is desirable to have a limiting stop and for this purpose the frame wall may be provided with a lug 31 recessed to contain 60 a fiber or other cushion 32. The rear end of the shank is provided with a lug 33 which carries an adjustable stop screw 34, the head 65 of which is arranged to contact the stop cushion 32.

65 The thread finger E is herein shown actu-

ating from the inner groove 16 of the cam disk 15 in the following manner. A cam roller or follower 37 is mounted on a cam lever 38, which is connected by link 39 with an arm 40 mounted in an adjustable manner 70 on a rock shaft 41. An adjusting connection 42, 43 between the link and arm permits change of throw of the thread finger E, which is adjustably mounted upon the shaft 41. The thread finger cooperates with the 75 looper in placing the thread upon the barb of the needle.

It only remains to describe the means and operation for locking forward and releasing the respective shanks of the work-rest 80 and back gage. These operations are all controlled by the cam 16 through a follower 44 mounted at the lower end of a cam lever 45 mounted on a rock shaft 46, all as seen in Fig. 1. The rock shaft passes through 85 the frame wall 10 to the opposite side, and the remaining connections are shown in Fig. 2. However, the locking devices themselves will be described first and later the controlling connections from the rock shaft 46. 90

It will be noted that the identical cam groove 16 is used to control both the thread finger E and the shank locking devices. It has been observed that the short period in which the locking is in effect is about a half 95 cycle removed from the thread finger actuation, and the groove has been adapted and arranged, through two separate followers, to effect both operations.

The devices for locking forward the work-rest and back gage respectively are of a 100 novel form and may be designated as grip arms 48 and 49 respectively. The construction is shown separately in Fig. 5. The grip member or arm 48 or 49 is shown as 105 a swinging member having a rounded or other blunt nose 50 adapted to contact upon and wedge against the smooth lateral surface of the shank *a* or *h*. This wedge arm is of a substantial length and fulcrumed 110 at a point 51 spaced laterally away from the shank, the distance and the length of the arm being such that when the nose is brought into contact with the shank the arm is inclined only slightly from the normal or 90 degree position. The mountings are firm and solid so as to give no yield. By this arrangement, when the grip arm is 115 brought into contacting position, as shown in Fig. 5, it affords an immediate gripping action, the shank being positively held against movement in a rearward direction, indicated by the arrow 52; while at the same time the device is capable of easy and 120 quick release, namely by simply pulling the grip arm slightly away from its gripping position.

The drawings show the grip members accommodated within recesses 53 in the frame wall 10, and each member has a spring 54 125

tending to press it into gripping position, which is shown in full lines, the retracted or non-gripping position being shown in dotted lines in Fig. 5. As each grip member constantly tends to assume gripping position and thus lock each shank against being forced rearwardly, it is only necessary to retract the grip members from gripping position at those periods in the cycle when it is not desired to lock the shank forward. The two shanks may be controlled simultaneously, and the connections for operating the grip arms may be as follows.

The rock shaft 46 heretofore mentioned, oscillated by the cam 16, carries a downwardly extending rock lever 56. The lower extremity of this is connected to swing a second lever 57 which is fulcrumed at 58. A loose connection between the two levers is necessary and this is provided by a block 59 pivoted on the lever 56 and engaging a slot 60 in the lever 57. The lever 57 extends downwardly at 61, and the lower extremity is provided with a pivot 62, connecting it to a link 63 which extends rearwardly and at 64 is connected near the lower end of the grip arm 49. The link 63 is extended forwardly beyond the pivot 62 and this extension 65 is similarly connected by a link 66 with the free end of the grip arm 48 by pivot 67. By this linkage a slight throw of the cam 16 is capable of moving both grip members 48 and 49 simultaneously into or out of gripping position. The same cam 16 is utilized that serves also to actuate the thread finger E. The connecting levers and links are proportioned and arranged to give the proper throw to the grip members at the proper points of time and to the proper extent. The timing of these operations with respect to the retracting movements, already described, will be understood by those skilled in the art and is also made clear by the contours of the cams herein shown. The described mechanism for operating and controlling the work-rest and back gage is simple, effective, quick-acting and durable.

In order to strengthen the mountings of the shanks *a* and *h* at their rear ends each of them may be provided with a confining plate 21, placed opposite to the gripping point at which the grippers 48 and 49 engage. The forward movement of the shank *a* may be limited by a stop pin 36 contacting the forward confining plate 20.

It will thus be seen that I have described a sewing machine of the class mentioned, embodying the principles and attaining the objects and advantages of the present invention. Since many matters of combination, arrangement, design, construction, and detail, may be variously modified without departing from the novel principles involved, no limitation to such matters is in-

tended except in so far as set forth in the appended claims.

What is claimed is:

1. In a shoe sewing machine, the operating shaft, and stitching instruments operated therefrom, in combination with a member, engageable with the work, a slidable shank carrying the member toward or from the work, and means for locking forward the shank at certain periods, comprising a pivoted, blunt-nosed grip-arm arranged to have its extremity swung into locking engagement with the sliding shank, at a slight incline from right angles to the surface of the shank, and connections from the operating shaft to said grip arm comprising an oscillating part and a connection therefrom to the grip arm operating both to thrust the grip arm into locking position and to swing it from position, in cooperation with the stitch forming operations. 85

2. In a shoe sewing machine, the operating shaft, and stitching instruments operated therefrom, in combination with a member, engageable with the work, a slidable shank carrying the member toward or from the work, and means for locking forward the shank at certain periods, comprising a pivoted blunt-nosed grip-arm arranged to have its extremity swung into locking engagement with the sliding shank, at a slight incline from right angles to the surface of the shank, and connections from the operating shaft to said grip arm comprising a rock lever oscillated from the shaft, and a link connection from the rock lever to the grip arm, moving the latter both to and from locking position. 95

3. In a shoe sewing machine a work rest, a back gage, sliding shanks therefor, a swinging grip arm for locking each shank forward, a rock lever, means for rocking it, and connections from said lever to both grip arms, comprising linkage operating both to force the grip arms into locking position and move them from gripping position. 105 110

4. In a shoe sewing machine a work rest, a back gage, sliding shanks therefor, a swinging grip arm for locking each shank forward, a rock lever, means for rocking it, and connections from said lever to both grip arms comprising a link from the rock lever to one of said grip arms, and a link from said link to the other of said grip arms. 115

5. In a sewing machine a member engageable with the work, and its slidable shank, a needle, a looper, a thread finger, a shaft, and connections for operating said elements, including a cam surface, two followers engaging said cam surface, connections from one follower to actuate the thread finger 125 and connections from the other follower for locking the shank forward.

6. In a shoe sewing machine a yielding

member engaged by the shoe, a yielding shank supporting said member, a shaft, a needle, a looper, a thread finger cooperating with the needle and looper, a cam actuated by said shaft, two independent followers engaging said cam, connections from one of such followers to the thread finger to operate it and means operated from the other follower for locking forward said shank at a certain part of each stitch cycle.

7. In a shoe sewing machine a yielding member engaged by the shoe, a yielding shank supporting said member, a shaft, a

needle, a thread handling instrument cooperating with the needle, a cam actuated by said shaft, two independent followers engaging said cam, connections from one of such followers to the thread handling instrument to operate it, and means operated from the other follower for locking forward said shank at a certain part of each stitch cycle.

In testimony whereof, I have affixed my signature hereto.

JOHN ROGER OLIVER.
